(57) **CLAIM**

The ornamental design for an electric plug connector, as shown and described.

DESCRIPTION

FIG. 1 shows a side view of my design for an electric plug connector, with the opposite side view being a mirror image thereof;

FIG. 2 shows a front view thereof;

FIG. 3 shows a rear view thereof;

FIG. 4 shows a bottom view thereof;

FIG. 5 shows a top view thereof;

FIG. 6 shows a top perspective view thereof; and,

FIG. 7 shows a bottom perspective view thereof.

The broken line portion of the figure drawings is included to show unclaimed subject matter and forms no part of the claimed design.
